DECK LID HINGE

Trygve Vigmostad and Earl W. Redick, Detroit,
Mich., assignors to Briggs Manufacturing Company,
Detroit, Mich., a corporation of Michigan

Application December 18, 1944, Serial No. 568,652

9 Claims. (Cl. 16—135)

1

This invention relates to hinge devices and more particularly to so-called deck lid hinges having especial application to swinging doors or lids of automobile or vehicle bodies, such as deck, trunk and hood lids thereof.

An object of the invention is to provide an improved hinge device of the foregoing character which is compact, strong and durable in construction while at the same time providing a unitary structure easily installed and occupying a minimum of space.

A further object of the invention is to provide a deck lid hinge or the like having spring controlled means of improved construction adapted to counterbalance, or substantially so, the weight of the lid or closure and to hold the same in raised position.

Another object of the invention is to provide a deck lid hinge having tension spring means mounted and operable in improved manner for counterbalancing the weight of the lid and assisting in the raising thereof.

Other objects of this invention will appear in the following description and appended claims, reference being had to the accompanying drawings forming a part of this specification wherein like reference characters designate corresponding parts in the several views.

Fig. 1 is a fragmentary perspective view of the rear end of an automobile body illustrating a deck lid hinged to the body by means of a hinge device constructed in accordance with the present invention.

Fig. 2 is a side elevation of the deck lid hinge illustrating the relation of the parts when the deck lid is in raised position.

Fig. 3 is a plan view of the deck lid hinge.

Fig. 4 is a side elevation of the deck lid hinge illustrating the relation of the parts when the lid is closed.

Fig. 5 is an enlarged section taken substantially through lines 5—5 of Fig. 4 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In Fig. 1 of the drawings there is illustrated an automobile body having a rear metal panel 10

2

forming a sloping deck, trunk or other compartment provided with an opening 11 into the compartment which is adapted to be closed by means of a swinging lid or closure 12 supported by means of a hinge device, generally designated at 13, constructed in accordance with the present invention.

In the illustrated embodiment the fixed member of the hinge 13 is in the form of a U-shaped stamped or pressed metal support 14 adapted to be rigidly secured by means of bolts 15 to the roof panel 16 of the compartment 11. The support 14 is a unitary stamping of inverted channel shape construction comprising a transverse front portion 14a and integral rearwardly extending legs or side members 14b extending in parallelism. As will be readily seen from the drawings, the support 14 comprises in section a top web engaging the underside of the panel 16 and depending spaced side flanges which terminate in laterally extending outer and inner edge flanges 17 and 18. Each of the sides or legs 14b of the U-shaped hinge frame 14 is bent downwardly at its rear end to provide a rearwardly and downwardly inclined portion 19 terminating below the panel 16 at or adjacent the margin of the deck opening 11.

In accordance with the present embodiment of the invention the movable member of the hinge device is in the form of a unitary generally U-shaped stamping comprising two spaced hinge members 20 integrally connected together at their outer ends by means of a transverse channeled plate or bar 21 rigidly bolted at 22 to the underside of the deck lid 12. Each of the hinge members 20 as well as the lid attaching portion 21 is pressed into channel shape and each member 20 intermediate its ends is bent into substantially a gooseneck 23. As illustrated in Fig. 5, each member 20 is formed with a relatively wide central web terminating in depending side flanges 24 turned outwardly along their edges to provide marginal flanges 25. Inwardly of the gooseneck 23 the side flanges 24 are progressively increased in depth so as to provide a channel shaped crank portion 27.

The side flanges 24 of each crank portion 27 embrace opposite sides of one of the depending legs 19 of the fixed hinge member 14. Each hinge member 20 is pivoted to the lower end of one of the depending legs 19 by means of spaced aligned shoulder rivets 26. As illustrated in Fig. 3, each rivet passes through one side flange 24 and the adjacent side flange of the channel shaped leg portion 19. From this construction it will be seen that each hinge member 20 is pivoted to one of the legs 19 by means of transversely spaced pivots

26, thus providing an unobstructed space or passage between the side flanges of the leg portion 19 for the free movement of the counterbalancing spring as hereinafter described.

Located below the hinge connections 26 of each of the hinge arms 20, when the lid is closed, is a transverse pin 28 connecting the side flanges 24 of the crank portion 27 and having its ends rigidly secured thereto as by riveting. Each pin 28 provides the connection for one end 29a of a heavy tension spring 29 which is hooked over the pin. Two of these springs are provided, as illustrated in Fig. 3, and each spring has its forward end 29b confined in a notch 30 in the flange 17 and hooked into a hole 31 in the backside of the support 14. Thus, the crank portion 27 at the inner end of each of the hinge members 20 is connected to the back of the fixed support 14 by means of a tension spring lying immediately below one of the sides 14b of the supporting frame and adapted to project into the downwardly opening channel thereof when the deck lid is in raised position, as shown in Fig. 2. In order to provide clearance for the movement of the rear ends of the springs 29 from the position shown in Fig. 4 to the position shown in Fig. 2, the top wall of each channel shaped leg 19 is cut away at 32. Likewise the flanging 17 along the lower edges of each leg 19 is cut away at 33 in order to provide clearance for the movement of the inner end of the hinge member 20.

When the deck lid 12 is raised to the position shown in Fig. 2 the springs 29, which are at all times loaded or under tension, exert a forward pull on the crank or lever portions 27 of the hinge members 20. The springs are so selected that the effective effort exerted by them is sufficient to substantially counterbalance the weight of the deck lid and thereby maintain it in its raised position. Since the rivets 26 of each pair forming the hinge connection for each hinge arm 20 are spaced apart, it will be seen that the spring 29 is permitted to pass between these rivets into the channel of the side member 14b during movement of the spring from the position of Fig. 4 to the position shown in Fig. 2. When the deck lid is lowered the spring connections 28 swing outwardly and downwardly thereby progressively stretching the springs and increasing the loading thereof. In the preferred construction each spring connection 28 moves a slight distance below a dead center line passing through the points 26 and 31 when the lid reaches its closed position as illustrated in Fig. 4. Hence, when the lid is in fully closed position the springs 29 will exert a slight effort tending to hold the lid firmly closed. Upon raising the lid from this position it will be seen that the springs will exert a progressively increasing lifting effort on the lid as soon as the springs have moved upwardly beyond dead center.

We claim:

1. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced hinge members pivoted at their inner ends to said side members to swing about a transverse axis, and tension springs connected at opposite ends to said support and hinge members, said springs extending horizontally in the verti-

cal planes of said side members when the lid is open and each movable within a slot in the channel of one of said downwardly bent ends and extending therethrough when the lid is raised.

5 2. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced inverted channel shaped hinge members telescoped with said downwardly bent ends and pivotally connected thereto to swing about a transverse axis, and tension springs lying below and in the vertical planes of said side members connected to the inner end of the support and also connected to the upper ends of lever portions on said hinge members extending upwardly above said axis when the lid is open and adapted to swing rearwardly of said axis and downwardly as the lid is swung to closed position.

20 3. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced hinge members pivoted at their inner ends to said side members to swing about a transverse axis, and tension springs connected at opposite ends to said support and hinge members, said springs extending horizontally in the vertical planes of said side members when the lid is open and each movable within a slot in the channel of one of said downwardly bent ends from a position above said axis to a position in which the spring intersects said axis.

25 4. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced inverted channel shaped hinge members telescoped with said downwardly bent ends and pivotally connected thereto to swing about a transverse axis, tension springs connected at their forward ends to the front edge of the support and extending rearwardly and horizontally at least partially within said side members when the lid is open, said hinge members terminating in lever arms extending upwardly from said axis when the lid is open and providing connections at their ends with the rear ends of the springs which connections are adapted to swing from points above said axis when the lid is open rearwardly of said axis and downwardly as the lid is moved to closed position.

30 5. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced inverted channel shaped hinge members telescoped with said downwardly bent ends and pivotally connected thereto to swing about

a transverse axis, tension springs connected at their forward ends to the front edge of the support and extending rearwardly and horizontally below said side members when the lid is open, said hinge members terminating in lever arms extending upwardly from said axis when the lid is open and providing connections at their ends with the rear ends of the springs which connections are adapted to swing from points above said axis when the lid is open rearwardly of said axis and downwardly as the lid is moved to closed position, said springs passing through said axis during closing movement of the lid.

6. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced hinge members pivoted at their inner ends to said side members to swing about a transverse axis, and tension springs connected at opposite ends to said support and hinge members, said springs extending horizontally in the vertical planes of said side members when the lid is open and each extending through and movable within a slot in the channel of one of said downwardly bent ends, said hinge members having lever arms extending upwardly from said axis when the lid is open and providing connections for the rear ends of said springs swingable rearwardly of said axis when the lid is moved to closed position.

7. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced inverted channel shaped hinge members telescoped with said downwardly bent ends and pivotally connected thereto to swing about a transverse axis, and tension springs lying below and in the vertical planes of said side members connected to the inner end of the support and also connected to lever portions on said hinge members at points lying above said axis when the lid is open and rearwardly of said axis when the lid is swung to closed position, the pivotal connection of each hinge member to one of said bent ends comprising pivots spaced apart to permit the adjacent spring to pass therebetween with the rear ends of the springs passing rearwardly of said axis as the lid is closed.

8. A hinge device for the swinging lid or closure of a compartment or the like, comprising a generally U-shaped support adapted to be mount-

ed within said compartment and having substantially parallel transversely spaced inverted channel shaped side members provided with downwardly bent outer ends, a hinge structure adapted to be secured to the lid and having spaced inverted channel shaped hinge members pivotally connected thereto to swing about a transverse axis, and tension springs lying below and in the vertical planes of said side members connected to the inner end of the support and also connected to lever portions on said hinge members at points lying above said axis when the lid is open, said points of connection of the springs to said lever portions adapted to move rearwardly of and below said axis when the lid is swung to closed position.

9. A hinge device for the swinging lid or closure of a compartment or the like, comprising a generally U-shaped support adapted to be mounted within said compartment and having substantially parallel transversely spaced inverted channel shaped side members provided with downwardly bent outer ends, a hinge structure adapted to be secured to the lid and having spaced inverted channel shaped hinge members pivotally connected thereto to swing about a transverse axis, and tension springs lying below and in the vertical planes of said side members connected to the inner end of the support and also connected to lever portions on said hinge members at points lying above said axis when the lid is open, said points of connection of the springs to said lever portions adapted to move rearwardly of and below said axis when the lid is swung to closed position, the rear ends of said springs projecting through openings in said bent ends and rearwardly thereof when the lid is open.
